(57) **CLAIM**

The ornamental design for a biometric door lock assembly, shown and described.

DESCRIPTION

FIG. 1 is a perspective view of a biometric door lock assembly showing my new design, shown in condition of use;

FIG. 2 is a front elevation view of the biometric door lock assembly;

FIG. 3 is a top plan view thereof;

FIG. 4 is a bottom plan view thereof;

FIG. 5 is a right side elevation view thereof; and,

FIG. 6 is a left side elevation view thereof.

The broken lines shown in the drawing disclosure are for illustrative purposes only and form no part of the claimed design.
